CONTAINER

William H. Pashley and Leland W. Oliver,
New York, N. Y.

Application June 29, 1933, Serial No. 678,202

4 Claims. (Cl. 206—65)

Our invention relates to an improved container as a new article of manufacture, and refers more specifically to a container in which inflammable objects may be stored or transported without appreciable fire hazard.

An important field of use for our invention, and one for which it was primarily designed, is the shipment and storage of cinematographic films. It is well known that such films are more or less inflammable and that, in consequence, regulations governing the storage and transportation of such films require that they be enclosed in containers as nearly fireproof as possible. The containers heretofore employed for this purpose are most usually metal drums or cases. These drums are fairly heavy and expensive. Inasmuch as great numbers of such films are shipped by air transportation and by parcel post for long distances, the weight of the container is a most important factor and any container which will combine substantial safety against fire danger with lightness of weight and cheapness of manufacture presents pronounced advantages over metal containers.

With the foregoing in mind, the principal object of our invention is to provide a shipping or storage container, mainly although not exclusively for cinematographic films, which is light in weight and substantially fireproof in the sense of being non-inflammable. We accomplish this object by forming the container of fireproofed corrugated board or paper, and if desired the container may contain a lining of asbestos or asbestos lined paper.

The container of our invention may take any form suitable for the purpose to be served, and by way of illustrating the application of the invention we have shown it embodied in a box or carton for the storage and shipment of cinematographic films.

In the accompanying drawing, Fig. 1 is a perspective view of such carton with the top flaps open and the contents disclosed; Fig. 2 is a section on the line 2—2 of Fig. 1, and Fig. 3 is a section of a fragment of the corrugated board of which the carton is made, an asbestos lining being shown in this figure.

The body of the carton is designated generally by the numeral 10 and is provided at the top and bottom with closure flaps 11, 12, 13 and 14. A permanent bottom closure is formed by applying non-inflammable adhesive to the outer and inner faces of certain of the flaps and then pressing such flaps together in overlapped or superimposed condition until firm interconnection is established.

An openable top closure is formed by folding the flaps 11 to 14 over one another in the usual manner and applying non-inflammable adhesive tape over the seams or edges of the flaps.

Within the carton is a series of compartments each constituted by a box or cell 15 which may be open at either end or at both ends. The boxes are arranged in close juxtaposition within the carton body 10 and preferably held therein by non-inflammable adhesive. Open ends of the boxes 15 are adjacent the openable top of the carton so that the drums of film 16, within the boxes 15, are easily accessible when the carton top is open. An intermediate portion of the edge of the wall at the open end of each box is notched 15 as at 17, the several notches being alined or registered to present a clearance for the fingers of a hand to engage the drums 16 and withdraw them selectively from the carton.

As shown in Fig. 3, the corrugated board is preferably double walled, consisting of the corrugations 10^a, the intermediate sheet 10^b and the face sheet 10^c. The carton body 10 with the flaps at both ends thereof is made of fireproofed corrugated board and the individual boxes 15 are also desirably, although they need not necessarily be, made of fireproofed corrugated board. A face sheet 10^c may, if desired, be asbestos protected as shown at 10^d.

Although the actual step of fireproofing the corrugated board is not a part of our invention, we prefer to employ a board which has been fireproofed by the addition of borax and boric acid, or ammonium sulfate to the pulp from which the board is manufactured, or applied to the paper during or after manufacture.

We have ascertained by exhaustive tests that a container of fireproofed corrugated board, embodying our invention, complies with all the requirements laid down by the competent authorities for the shipment and storage of inflammable substances; consequently our invention provides a container much lighter in weight and more economical of production and use than prior art containers for similar purposes.

We claim:

1. A light weight shipping compartment container comprising walls made of flexible fibrous material and strengthened by corrugations within the structure of said material, the wall structure of the container having a fireproofing material impregnating the same, a plurality of the compartments being so shaped and dimensioned as to house neatly rolls of cinematographic film. 55

2. A container according to claim 1 and in which the fibrous material is corrugated board.
3. A container according to claim 1 and having end flaps of the same material as the walls of the container.
4. A container according to claim 1 and in

which the partitions between the compartments are of the same material as the walls of the container and are notched to permit easy access to the film rolls.

WILLIAM H. PASHLEY.
